CLAIM

The ornamental design for a bath liner, as shown and described.

DESCRIPTION

FIG. 1 is an isometric view of a bath liner showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof; and,

FIG. 7 is a bottom plan view thereof showing my design. The broken lines in the drawings represent environment. No claim is made to the mounting members underneath the bath liner shown in broken lines.
